DESIGN FOR A HAIRBRUSH

Joseph W. Mayer, Troy, N. Y., assignor, by mesne assignments, to Tek Hughes, Inc., a corporation of New York

Application December 13, 1946, Serial No. 135,480

Term of patent 14 years

(Cl. D86—10)

To all whom it may concern:

Be it known that I, Joseph W. Mayer, a citizen of the United States, residing at Troy, in the county of Rensselaer and State of New York, have invented a new, original, and ornamental Design for Hairbrush, of which the following is a specification, reference being had to the accompanying drawing, forming a part thereof in which—

Fig. 1 is an elevational view of a hairbrush, showing my new design; and

Fig. 2 is an end view thereof.

The essential features of my design are shown in full lines.

I claim:

The ornamental design for a hairbrush, as shown and described.

JOSEPH W. MAYER.
